C. R. TOMPKINS, OF ROCHESTER, NEW YORK.

Letters Patent No. 70,051, dated October 22, 1867.

IMPROVEMENT IN MORTISING MACHINES.

The Schedule referred to in these Letters Patent and making part of the same.

TO ALL WHOM IT MAY CONCERN:

Be it known that I, C. R. TOMPKINS, of Rochester, in the county of Monroe, and State of New York, have invented certain new and useful "Improvements in Mortising Machines;" and I do hereby declare that the following is a full, clear, and exact description thereof, reference being had to the accompanying drawings, making part of this specification, in which—

Figure 1 is a side elevation of my invention applied to an ordinary mortising machine, a portion of the frame being broken away to show the relative arrangement of the parts.

Figure 2 is a detached view of the ratcheted reversing-barrel, sleeve, and collars.

Figure 3 is a plan of the ratchet or clutching collar.

Figure 4 is a top view of the head or flange *d*, showing the notches *u* into which the V-shaped head of the clutch *t* takes.

Like letters of reference indicate like parts.

This invention relates to that class of mortising machines having an automatically reversing chisel-stock; and its nature consists in the employment of such an arrangement of devices as will cause the chisel-stock to retain a fixed position upon its axis until the chisel is entirely withdrawn from the timber, when it will be reversed by the extreme downward movement of the table.

To enable others to make and use my invention, I will describe its construction and operation.

I provide a chisel-stock or mandrel, *M*, with a feathered sleeve, *S*. This sleeve has two heads or collars, *b* and *d*, between which it has its journal-bearing in the box *B*. The upper portion of the sleeve is encircled by a loose barrel, *R*, which is secured to the sleeve by a collar, *f*, and set-screw *s*, fig. 2. The point of this screw may be made to act as the feather, by entering the slot or groove in the shaft or stock *M*, as shown, or an ordinary feather or key may be applied to the sleeve. The barrel *R* is provided with a spiral groove, *g*, (fig. 1,) in which the end of the lever *D* moves. I place a ratchet catch or pawl, *a*, in the lower end of the barrel *R*, as shown in fig. 2. It is forced down by a suitable spiral spring, *n*, and catches in the recesses or notches *o* made in the upper face of the collar *b*, as shown in figs. 2 and 3. The lower head *d* of the sleeve *S* has two V-shaped notches in its periphery, into either of which the corresponding shaped edge of the locking-bolt *t* is forced by the spring *v*, fig. 1. The chisel-stock is swivelled to the cross-head *H*. The adjusting-rod *E* passes through the lever *D*, and is provided with a spiral spring, *J*, the lower end of which rests upon the lever, and the upper end against the set-nut *r*. The lever is hinged to the frame of the machine by the rock-shaft *F*. There is an adjustable locking-bar, *y*, through which the lever *D* passes, the bar being slotted to receive it. The chisel-mandrel or stock is reciprocated by the pitman *P* from the fly-wheel *W*. When the mortising-table *T* descends, the spring *J* is gathered or compressed until the coils are all closed together, which may be made by a set-nut, *r*, to take place just before the table shall have reached the limit of its downward throw, and the spring thus becoming rigid forces the bar or lever *D* down, and the barrel *R* to turn, by forcing the clutch *t* to release the head *d*, and the expansion of the spring drives the end of the lever down to the lower end of the spiral groove *g*. The locking-latch having already fallen with its wing *e*, before the pin *i*, which prevents the possibility of the head *t* failing to catch in the notch in the head *d*. When the table works up to the position shown in fig. 1, the barrel *R* is turned backward, and the ratchet *a* catches in the opposite notch, and the locking-latch *y* is raised, as shown, releasing the pin *e*, which will pass under the wing *e* before the latch drops at the next descent of the table, the chisel-stock being firmly held in the mean time in position by the head or catch *t*. The nut *p* may be made adjustable upon the rod *E*, to admit of the necessary changes in the elevation of the mortising-table *T*.

What I claim as my invention, and desire to secure by Letters Patent, is—

The arrangement of the adjustable spring-rod *E*, lever *D*, reversing scroll-collar *R*, collared sleeve *S*, with its projections *i*, locking-bar *y*, and the spring catch *t*, substantially in the manner and for the purposes herein shown and described.

C. R. TOMPKINS.
